UNITED STATES PATENT OFFICE.

EDWARD N. MIMMS AND CLAUDE MIMMS, JR., OF GUTHRIE, KENTUCKY.

LUBRICATING SYSTEM FOR ENGINE CRANK CASES.

Application filed September 25, 1920. Serial No. 412,635.

To all whom it may concern:

Be it known that we, EDWARD N. MIMMS and CLAUDE MIMMS, Jr., citizens of the United States, residing at Guthrie, in the 5 county of Todd and State of Kentucky, have invented certain new and useful Improvements in Lubricating Systems for Engine Crank Cases, of which the following is a specification.

10 This invention relates to a lubricating system for internal combustion engines and combines the advantages of splash lubrication with those of a continuous circulation of oil and is especially adapted to be used 15 with a Ford engine although not limited to this particular type.

In some motor designs employing splash, a well is provided so that the fly wheel revolves in a bath of oil. In turning, due to 20 centrifugal force, the fly wheel projects the oil adhering to it with great force. Part of the oil thus thrown out is caught by a tube opening into the path of oil, and is led forward over the distribution gears. On its 25 return to the lowest part of the crank case the oil feeding over the distribution gears fills up the connecting rod trough. In this way it is kept in continuous circulation. All 30 parts of the clutch and transmission are lubricated in the same manner, as are the motor parts. It is well known that in this fly wheel splash system it is necessary to avoid excess oil above a certain level which is usually indicated by a level cock. It has 35 been found desirable to keep the oil even lower than this level cock in the crank case and it is the object of the present system to keep the oil in the fly wheel comparatively low thereby decreasing the amount of oil 40 used and consequently preventing carbon from collecting on the spark plugs, cylinder heads, pistons, et cetera, as is usual in this system where an excess of oil is being used.

A further object of the invention is to 45 generally improve upon systems of this nature by providing one which will be of extremely simple, durable and inexpensive construction, one which is efficient and reliable in operation and well adapted to the purpose 50 for which it is designed.

With these and numerous other objects in view, the invention resides in certain novel features of construction and the combination and arrangement of parts as will be 55 hereinafter fully described and claimed.

In the drawings—

Figure 1 is a fragmentary side elevation of the crank case of an internal combustion engine showing our invention thereon,

Figure 2 is a section taken on the line 2—2 of Figure 1,

Figure 3 is a side elevation of a receiving tank which may be attached to crank cases now in use,

Figure 4 is a fragmentary side elevation of a portion of a crank case showing a modified form of the invention as illustrated in Figure 1, and

Figure 5 is a section taken on the line 5—5 of Figure 4.

Referring to the drawings by numerals it will be seen that 1 designates the crank case which may be of any preferred construction having the usual crank case cover 2 thereon. Adjacent the crank case 1 there is provided 75 the fly wheel well casing 3 having the usual cover 4. To the other side of this fly wheel well casing 3 there is disposed the transmission case 5 having its cover 6. The parts thus far described are of a conventional form and 80 well known in the arts and may be of any preferred construction.

Disposed immediately below the transmission case 5 we have provided a receiving tank and as shown in Figure 1, this 85 receiving tank 7 is formed integrally with the crank case 1, fly wheel well casing 3 and transmission case 4. A partition 9 separates the receiving tank 7 from the fly wheel casing 3 and is provided adjacent 90 its upper portion with an opening 10 and adjacent its lower portion with an opening 11 which will be much smaller than the opening 10 as clearly shown in Figure 2 of the drawing. The fly wheel well casing 3 95 is provided with the usual oil drain plug 8 so that it and the receiving tank may be drained when desired. It should also be noted that the lower portion or bottom of the receiving tank 7 is slanted toward the 100 fly wheel well casing 3 so that the oil will naturally flow through the opening 11 should the rear portion of the crank case be lower than the forward portion. As is well known the fly wheel revolves in the fly 105 wheel well casing at considerable speed and throws the oil in all directions and it is the object of this invention to accumulate the excess oil in the receiving tank 7.

This receiving tank 7 is provided with 110

the oil cocks 12 and 13 at its rear end which will be at approximately the same height as the oil cocks now commonly placed upon the fly wheel well casing. As stated above 5 it is desirable to have the oil at a comparatively low level in the fly wheel casing and it is the purpose of this invention to collect the excess oil in the receiving tank 7 since the spray will force a portion of the excess 10 oil into the opening 10 and other oil along the face of the partition 9 will pass through the opening 10 into the receiving tank 7 and accumulate therein since the opening 11 will only slowly deliver the oil into the 15 fly wheel well casing as compared to the speed with which the oil will be fed into the receiving tank because of the comparative largeness of the opening 10. It is our purpose to place considerable more oil in the 20 crank case than is now the custom so that the engine may run for a longer time without the necessity of replenishing the oil. Of course, when the engine is first started the level of the oil will be comparatively 25 high in the fly wheel well casing but after the engine has run for a very short length of time the excess oil will have been delivered to the receiving tank 7 and the level in the fly wheel well casing 3 will be at a comparatively low point.

In Figures 4 and 5 of the drawing we have shown a slight modification of my invention whereby instead of using the large opening 10 we provide a hollow arm 14 which 35 communicates with the side of the fly wheel well casing 3 and the side of the receiving tank 7 as is clearly shown in Figure 4. By this modification a still greater amount of oil may be placed in the crank case and will 40 be quickly delivered to the receiving tank owing to the fact that the centrifugal force of the fly wheel will naturally throw the oil into this arm 14. As noted in Figure 4 this arm will slant toward the receiving 45 tank 7 so that the oil will readily flow thereinto.

In Figure 3 of the drawing we have illustrated an attachment receiving tank 7' which is built so as to fit snugly under the 50 transmission case 5 and adjacent the fly

wheel well casing 3. This receiving tank 7' is provided with a pipe 15 leading from the top thereof to the top of the fly wheel well casing. The receiving tank attachment 7' also communicates with the bottom 55 of the fly wheel well casing by means of a nipple 16. It will readily be understood that any desired means may be used for attaching this receiving tank 7 to the transmission case and fly wheel well casing and 60 it is, therefore, not necessary to here illustrate these details.

From the foregoing description, taken in connection with the accompanying drawings the construction and operation of the 65 invention will be readily understood without a more extended explanation. Numerous changes in form, proportion, and in the minor details of construction may be resorted to without departing from the spirit 70 of this invention, though we do not wish to be limited to the construction herein shown other than as claimed.

Having thus described our invention, what we claim as new is:

1. A receiving tank formed so as to fit below the transmission case and abut the fly wheel well casing of an internal combustion engine, means provided at its lower end for communicating with the fly wheel well casing and means provided at its upper end for also communicating with said casing. 75

2. In a system of the class described, a receiving tank formed so as to fit below the transmission case and abut the fly wheel 80 well casing of an internal combustion engine and having its bottom slanting toward the fly wheel well casing, means provided at its upper end for communicating with the fly wheel well casing, and means provided at its lower end for communicating with the same. 85

In testimony whereof we affix our signatures in presence of two witnesses.

EDWARD N. MIMMS.
CLAUDE MIMMS, JR.
